UNITED STATES PATENT OFFICE.

FRED SCHUMANN, OF BROOKLYN, NEW YORK.

SCREW-LOCK AND SLOT-FILLER.

1,257,537.

Specification of Letters Patent. Patented Feb. 26, 1918.

Application filed November 24, 1914. Serial No. 873,685.

To all whom it may concern:

Be it known that I, FRED SCHUMANN, a citizen of the United States, residing in Brooklyn, in the county of Kings and State 5 of New York, have invented certain new and useful Improvements in Screw-Lock and Slot-Filler, of which the following is a specification.

My present invention relates to an improvement in slot-filters for screws and the like wherein the head thereof is slotted and more especially relates to use in conjunction with wood screws of the well known type.

15 In some uses to which screws are put, the slot is usually necessary for the insertion of a screw-driver or like tool for applying the screw. This slotted head is rather unsightly especially where slotted head screws only 20 are utilized for holding ornamental panels and the like.

25 The important advantage of my device is that after the screw has been applied, the filler may be driven into the slot thereof, thereby filling the slot and making the screw fastening means of a more slight appearance and at the same time making it very difficult to extract the screw thereafter.

Another important feature of my device 30 is that it prevents the backing out of the screw by vibration, or through the shrinkage of the wood in which it may be placed owing to the action of the locking point on the filler as well as filling up the slot in such 35 a manner as making difficult the removal by the customary screw-driver.

In the drawing, Figure 1 is a perspective transparent view of a screw-lock and slot-filler, as the same appears when in locking 40 position, on the upper portion of a screw, of rounded or button-head form; Fig. 2 is a side view of the complete-screw and lock in locking position partially in section, one side of the head, shank, and slot 45 being broken away; Fig. 3 is a top view in detail removed from the screw of the slot-filler and lock-member; and Fig. 4 is a like side-view thereof.

To form my improved screw-lock, etc., I 50 take a screw of any suitable ordinary form, the shape of the head being immaterial, but in each case the slot-filler head is of such form as to fill completely, and fit snugly in the drive-slot of the screw-head. The screw

shown herein is of what is commonly known 55 as the "rounded" or "buttonhead" form of wood-screw 2, 2^a. Through this screw beginning at or adjacent to the center of the drive-slot of the screw-head, I drill diagonally downward and outward through the 60 screw-shank 2, a bore hole 11, preferably, but not necessarily, in the plane of the drive-slot of the screw head 1, in which snugly fits the slot-filler disk 9^a of the same exterior contour as the head having the diagonal 65 preferably sharp-pointed securing prong 10 formed integral therewith, or firmly secured to the bottom plane face thereof angular to such bottom plane face, in such manner that when the slot-filler disk 9^a is driven down 70 into position in the drive-slot, such prong 10 will be forced down and out through the bore 11 in such manner as to lock the screw against rotation.

It is evident that many changes and modifications in the construction of my invention may be made without departing from the scope thereof; and I do not intend to limit myself to the exact construction shown.

I claim:

1. In combination with a screw having a screw-slot and an opening extending downwardly from the base of the screw-slot through the shank of the screw at an angle to the base of the screw-slot in the plane 85 thereof; of a slot-filler having a disk member corresponding to the dimensions of the screw-slot to accurately fill the same; and a prong extending downwardly from said disk member at an angle thereto to extend 90 through the inclined opening of said screw-shank in the plane of the disk.

2. In combination with a screw having a screw-slot and an opening extending downwardly from the base of the screw-slot 95 through the shank of the screw at an angle to the base of the screw-slot, of a slot-filler having a disk member corresponding to the dimensions of the screw-slot to accurately fill the same, and a prong extending downwardly from said disk member at an angle thereto to extend through the inclined opening of said screw-shank. 100

FRED SCHUMANN.
